[57] CLAIM

The ornamental design for a combined pharmaceutical discharge apparatus and lid, as shown and described.

DESCRIPTION

FIG. 1 is a front elevational view of a combined pharmaceutical discharge apparatus and lid, showing my new design with the lid removed;

FIG. 2 is a side elevational view thereof;

FIG. 3 is an opposite side elevational view thereof;

FIG. 4 is a top plan view thereof;

FIG. 5 is a bottom plan view thereof;

FIG. 6 is an opposite front perspective view thereof;

FIG. 7 is a front elevational view thereof with the lid attached;

FIG. 8 is a side elevational view thereof;

FIG. 9 is an opposite side elevational view thereof;

FIG. 10 is a top plan view thereof;

FIG. 11 is a bottom plan view thereof;

FIG. 12 is an opposite front perspective view thereof; and,

FIG. 13 is another front perspective view thereof, with the lid in separated condition.
